PIPE FITTING

Herbert C. Schulze, 3690 Highland Drive,
Carlsbad, Calif.

Filed Feb. 24, 1964, Ser. No. 78,745

Term of patent 14 years

(Cl. D91—3)

FIG.1

I claim:

The ornamental design for a pipe fitting, substantially as shown.
